APPARATUS FOR PRODUCING HIGH-VOLTAGE CURRENTS FOR MEDICAL TREATMENT.

Application filed November 11, 1924. Serial No. 749,322.

To all whom it may concern:

Be it known that I, ERICH GEISSLER, a German citizen, and residing at Munich-Laim, Germany, have invented certain new and useful Improvements in an Apparatus for Producing High-Voltage Currents for Medical Treatment, of which the following is a specification.

The hitherto known apparatus for producing high-voltage currents for medical treatment are provided with a separate switching-on and adjusting device and can be used with special electrodes only. The adjustment of the intensity of current as well as the application of the electrodes to the human body is mostly much feared and irksome, because according to the choice of the electrodes and with a too strong adjustment of the current intensity burnings occur frequently, apart from breaks of the glass electrodes if using the same for treating inner parts of the human body.

The present invention overcomes said drawbacks by the provision of means for permanently keeping the apparatus adjusted to a normal intensity of current and automatically effecting the closing of the circuit during its use. Thus, the admission of the high-voltage currents to the human body takes place almost unperceivably.

The automatic switching-on or closing of the circuit is effected by the current applicator (button-shaped electrodes of glass or metal), which is connected with the secondary (Tesla) coil in a detachable but conductive way.

The closing of the circuit is effected by a depression of the electrode by means of a human member or by pressing the same against any place of the human body. Of course, the electrode can also be operated in any other way for switching-on the current or for a displacement of the secondary coil, for instance by its rotation, a lever transmission, or any other appropriate mechanism. As the electrode is connected with the secondary coil, the latter is displaced against the action of springs and thereby the contacts, and thus the circuit, are closed, whereupon the high-voltage currents produced are admitted to the human body. By ceasing the pressure on the electrode, the circuit is again interrupted.

The advantages of the improved arrangement consist in avoiding errors of control and thus the production of noxious currents and finally a formation of sparks when applying the electrodes to the human body. The latter is almost unperceivably charged with currents of high-voltage, whereupon the members to be cured are treated directly or with the aid of any appropriate instrument by a second person connecting himself to the circuit like a condenser and whereby at the place in question the current is taken from the human body.

If an artificial earthing is created, for instance by leading back the electric current to the condenser of the apparatus through a second electrode or instrument arranged in an insulated handle and in contact with the current-charged body, the current receiving patient himself can also carry out the treatment of the respective places on his own body.

For a removal of warts, corns, beauty spots, or the like, no separate electrodes as hitherto are required, because any metal implement can be used for the purpose in question. Of course, also the known glass or metal electrode can be used for treating the human body at the places in question.

The apparatus essentially comprises a secondary coil, a primary coil, and a condenser; said parts being assembled in any appropriate shape, for instance in a box, tube, column, or the like, only the current supply and the electrode for switching-on the current being visible from outside.

In the accompanying drawing, Figs. 1 to 3 show the apparatus shaped like a box, and Fig. 4 like a tube; Fig. 1 being a sectional side view on the line B—B of Fig. 3; Fig. 2 a sectional side view at right angles to that of Fig. 1; Fig. 3 a sectional plan view on the line A—A of Fig. 1; and Fig. 4 a side view.

Referring to Figs. 1 to 3 inclusive: The apparatus is enclosed by a casing *a*. The secondary coil *b* consists, as usual, of a core *c*, the oilpaper coating *d*, with the secondary windings *e*, the glazed paste-board tube *f*, and the primary windings *g* leading at one end to the condenser *h* and at the other end to the interrupter (magnetic hammer break) *i*. The secondary coil *b* is slidably mounted

on pins *k* encircled by coil springs *l* which tend to keep said coil in its inoperative position. A metal disc *m* at the bottom end of the secondary coil is provided with one contact *n*; the other contact *o* being located underneath and connected with the interrupter *i*. The metal disc *m* is connected with the middle part of the three-part plug *p*, the three parts of which serve to use the apparatus for different current voltages. As usual, of the two remaining lateral plugs one is connected to the whole winding of the primary coil *q* and the other to part of said winding only. According to the current voltage in the line, the plug box cover connected with the latter is attached to either of these two plugs *p*.

The primary coil *q* is of ordinary construction, the interrupter *i* being mounted thereon, the discs *r* arranged on the latter serving as radiating coolers.

In the core *c* of the secondary coil *b* a sleeve *s* is inserted and designed to receive the electrode shell *t*, in which the electrode *u* is detachably inserted.

To make the apparatus operative, the electrode *u*, and thus also the secondary coil *b*, is depressed against the action of springs *l*, whereby the contacts *n*, *o* and thus the circuit are closed. By ceasing the pressure on the electrode, the circuit is again interrupted.

For an auto-treatment, a second electrode or metal instrument *v* is provided and ar-

ranged on an insulated handle *w*, a wire *x* serving to lead back the current to the condenser *h*, said wire being connected thereto by means of a plug in order to be attached to or removed from the apparatus as desired.

Referring to Fig. 4: The apparatus is here built in a tube *y* of non-conducting material. For its use, the electrode *u* is depressed and thereby the current supplied through wires *z* is switched on.

The apparatus allows an easy manipulation and is applied to the human body by pressing the electrode *u* thereon whereby the circuit is automatically closed.

What I claim, is:—

1. In an apparatus for producing high-voltage currents for medical treatment, the combination with an electrode consisting of glass and forming a contact button, of means for closing the circuit by pressing said contact button on part of the human body.

2. In an apparatus for producing high-voltage currents for human cure; the combination with a casing enclosing the apparatus and an electrode protruding from said casing, of means for automatically closing the circuit and again automatically interrupting the same by said electrode during use of the apparatus.

In testimony whereof I have hereunto set my hand.

ERICH GEISSLER.
